FLOOR MAT FOR AUTOMOBILES AND THE LIKE

Emanuel Meyer, 23 Latham Parkway, Melrose Park, Pa.

Filed July 25, 1961, Ser. No. 66,060

Term of patent 14 years

(Cl. D9—6)

FIG. 3 -

FIG. 1 is a top plan view of a floor mat for automobiles embodying my new design;

FIG. 2 is an enlarged fragmentary section on line II—II; and

FIG. 3 is an enlarged fragmentary top plan view of the portion shown in full lines in FIG. 1.

The dominant feature of my design resides in the portion shown in full lines.

I claim:

The ornamental design for a floor mat for automobiles and the like, as shown and described.
